H. M. GUSDORF

PULLEY

Filed Feb. 12, 1923

Inventor,
Harold M. Gusdorf,
By Joseph A. Minturn
Attorney.

UNITED STATES PATENT OFFICE.

HAROLD M. GUSDORF, OF INDIANAPOLIS, INDIANA.

PULLEY.

Application filed February 12, 1923. Serial No. 618,484.

To all whom it may concern:

Be it known that I, HAROLD M. GUSDORF, a citizen of the United States, residing at Indianapolis, in the county of Marion and 5 State of Indiana, have invented new and useful Improvements in Pulleys, of which the following is a specification.

The object of this invention is to provide a pulley with a belt surface pitted with 10 elastic cup-like depressions that will give a vacuum-grip on the belt, and which will have a substantially inelastic side contacting the pulley-face to insure a stronger and more durable attachment to the pulley of 15 the said outer material.

A further object is to utilize hog-skin leather, tanned to preserve the desired in- 20 elastic grain surface and elastic flesh side with cup-formations natural to it for the pulley facing material.

I accomplish the above, and other minor objects such as will hereinafter appear, by the means diagrammatically illustrated in the accompanying drawing, in which—

25 Fig. 1, is a cross section of hog-skin leather, greatly magnified, to show the interwoven fibres that impart a firm surface to the leather on the grain side, and the cup-like indentations of the other or flesh side. Fig. 2, is a side elevation of a pulley 30 faced with hog-skin leather, and Fig. 3 is a front or face view of same.

Like characters of reference indicate like parts in the several views of the drawing.

35 The pulley 4 is of iron, steel, wood or other usual and suitable material made in the usual manner and of any desired size. The face 5 of the pulley is covered with

hog-skin leather with the firm inelastic grain or hair-side 6 in contact with the pulley surface and the opposite flesh side 7 turned outwardly. This flesh side 7 is pitted with cup-like depressions 8, natural to hog-skin and carefully preserved in the process of tanning, and the adjacent material of 45 the hog-skin to said cups is sufficiently elastic to allow them to be compressed under a load, thereby discharging much of their contained air, and to spring back due to said elasticity thereby creating partial vacuums 50 which cause the pulley surface made from said leather to grip the belt.

The hog-skin leather will be cemented to the pulley face, or securely attached thereto in any suitable manner.

While I have here illustrated and de- 55 scribed hog-skin leather as a natural prod- 60 uct when suitably treated in tanning, a pulley-facing material having the same essen- 65 tial characteristics may be produced en- tirely by artificial means, and I do not de- scribe therefore to limit my invention to hog- skin or any certain material, more than is required by the appended claims.

I claim:

1. A surface cover for pulleys made out of hog-skin having the grain side next to the pulley and the flesh side out.

2. The combination, with a pulley, of a facing therefor formed out of hog-skin 70 leather having the grain side secured to the pulley and the flesh side out to be contacted by a belt.

Signed at Indianapolis, Indiana, this the 6th day of February, 1923.

HAROLD M. GUSDORF.
